D175,202 S 7/1955 Tupper
2,780,385 A 2/1957 Tupper*Primary Examiner* — Ricky Pham(74) *Attorney, Agent, or Firm* — Taylor J. Ross(57) **CLAIM**

The ornamental design for a vent for a food container, as shown and described.

DESCRIPTION

FIG. 1 is a top, side and front perspective view of a vent for a food container showing our new design;

FIG. 2 is a bottom, side and front perspective view thereof;

FIG. 3 is a top plan view thereof;

FIG. 4 is a bottom plan view thereof;

FIG. 5 is a right side elevation view, the left side being a mirror image thereof;

FIG. 6 is a front elevation view thereof;

FIG. 7 is a rear elevation view thereof; and,

FIG. 8 is a cross-sectional view along line **8-8** of FIG. 3.

The broken lines shown in the drawings are for illustrative purposes only and form no part of the claimed design.
